MARINE MINE

John L. Thompson, Edgewater Park, N. J., and
Donald E. Marlowe, Takoma Park, Md.

Application February 19, 1944, Serial No. 523,088

9 Claims. (Cl. 102—7)

(Granted under the act of March 3, 1883, as
amended April 30, 1928; 370 O. G. 757)

1

This invention relates to marine mines and more particularly to ground mines of the marine type adapted to be planted from an aircraft in flight and come to rest on the bed of a body of water within the path of travel of a vessel.

In ground mines heretofore devised of the type adapted to be planted within a body of water from aircraft in flight, it has been the usual practice to provide the mine with a casing generally cylindrical in shape and having either a flat or rounded end portion or nose thereon. The path of travel of the mine through the air is usually controlled by a plurality of fins formed integrally with or secured to the mine casing, as the case may be, or by a parachute detachably secured to the tail end of the mine, the parachute serving additionally to decrease the rate of travel of the mine through the air. These mines have not been found to be entirely satisfactory under the conditions of service for the reason that the mine may possess a sufficiently high velocity at the moment of striking the bed of the body of water within which the mine is planted as to cause the mine to sink deeply into the bed if the mine is planted in a body of water having a relatively soft bed and thereby impair the effectiveness of the mine in detecting and destroying a surface vessel by increasing the distance of the mine from the vessel which the mine is adapted to destroy and by reason of the impairment of the destructive effect and confinement of the explosion of the mine to a relatively small area of the water. There is also a possibility that the mine may fail to arm by reason of the thick layer of mud within which the mine is encased causing the failure of certain soluble washers, plugs and the like to dissolve and the hydrostatic arming devices controlled thereby to operate. Furthermore, the problem of locating and recovering mines is greatly increased when the mines are buried within the bed of the body of water.

In the case of a body of water in which the bed is relatively hard, the launching of the mine therein from an aircraft in flight may cause the mine to strike the bed with sufficient force to damage or destroy the firing control mechanism, or crack the casing of the mine thereby flooding the mine with water and rendering the mine useless.

In accordance with the present invention, the mine retains all of the advantages of the prior mines of this general type and possesses none of the foregoing disadvantages. More specifically, the invention provides an arrangement in which the course of the mine within the water is

2

abruptly changed by reason of the provision of a member which is forcibly detached from the casing of the mine as the mine strikes the surface of the water thereby exposing a control surface to the water and causing the mine to be deflected from its initial downward course and engage the bed of the body of water at a greatly reduced rate of travel, whereby the mine comes to rest on the bed without damage or injury to the mine casing or to the firing control mechanism arranged therein.

One of the objects of the present invention is the provision of new and improved means for suddenly reducing the velocity of an aircraft planted mine during the travel of the mine through the water and thereafter allowing the mine to sink at a reduced rate of travel within the water.

Another of the objects is the provision of new and improved means for substantially arresting the downward movement of a submerged aircraft planted mine during the travel of the mine within the water and thereafter allowing the mine to sink within the water at a reduced rate of travel.

Still another object is the provision of new and improved fairing on the mine case adapted to be detached therefrom as the mine strikes the surface of a body of water when dropped from a considerable altitude thereby to cause the downward movement of the mine within the water to be reduced to a value equal to or less than the terminal velocity of the mine within the water.

A further object is the provision of new and improved means for causing a mine to follow a predetermined line of flight through the air when launched from an aircraft and to follow an erratic path of travel through the water.

A still further object is the provision of new and improved means for preventing an aircraft planted ground mine from being buried within the bed of a body of water during the launching thereof.

Still other objects, advantages and improvements will become apparent from the following description taken in connection with the accompanying drawings of which:

Fig. 1 is a view of a mine according to a preferred embodiment of the invention;

Fig. 2 is an end view of the mine of Fig. 1;

Fig. 3 is a fragmentary view taken along the line 3—3 of Fig. 2;

Fig. 4 is an end view of a mine according to an alternative form of the invention;

Fig. 5 is a fragmentary view partly in section taken along the line 5—5 of Fig. 4; and,

Fig. 6 is a plan view partly broken away of the mine of Fig. 4.

Referring now to the drawings for a more complete understanding of the invention and more particularly to Fig. 1 thereof there is shown thereon a mine indicated generally by the numeral 10 comprising a cylindrical casing 11 having a rearwardly extending tapered portion 12 provided with a plurality of brackets 13 secured thereto in any suitable manner and adapted to receive and support, if desired, a plurality of fin members, as is well known in the art. The rear or tail portion of the casing is enclosed by a cap 14 secured in any suitable manner to the tapered portion 12 of the casing. There is also secured to the tail end of the casing an annular member 15 adapted to be engaged by a clamping ring or other suitable device and thereby secure to the mine a parachute, if desired, the parachute being adapted to be detached from the mine casing in any well known manner as the mine strikes the surface of the water when launched from an aircraft in flight.

The casing 11 is preferably provided with brackets 16 and 17 thereby to facilitate the loading of the mine into the aircraft and, if desired, to secure the mine to the aircraft prior to the launching of the mine therefrom. The mine is also preferably provided with a hydrostatically controlled arming device 18 adapted to be actuated by the pressure of the surrounding water when the mine has been planted for a length of time sufficient to dissolve or soften the soluble washer associated therewith. The mine is also preferably provided with a hydrostatically controlled detonator extender mechanism 19 adapted to move the detonator to an armed position within the mine by the pressure of the surrounding water when sufficient time has elapsed to dissolve or soften a soluble washer or plug associated therewith.

The leading end or nose of the mine is preferably enclosed by a plate 21 of semicircular shape having welded thereto as at 22 a second plate 23 inclined at an angle substantially as shown. The plates 21 and 23 are of sufficiently rugged construction to withstand the shock of impact of the mine against the surface of the water and against the bed of the body of water respectively without damage or injury thereto, the plates 21 and 23 being secured to the casing 11 of the mine in any suitable manner as by welding the parts together thereby to form a watertight joint between the end plates and the casing. The plate 21 is provided with an aperture adapted to be sealed by a cover or cap 24 secured thereto as by the bolts 25, the cap being preferably arranged to support one end of an induction coil arranged within the casing of the mine and employed for detecting variations in the magnetic field adjacent thereto caused by the approach of a vessel within the vicinity of the mine and thereby fire the mine beneath the vessel. The induction coil and mine firing control mechanism associated therewith may be of any type suitable for the purpose such, for example, as the induction coil disclosed and claimed in the copending application of Robert H. Park et al. for Magnetic detecting device, Serial No. 500,400, filed August 28, 1943, and the mine firing control mechanism disclosed and claimed in the copending application of James B. Glennon et al. for Mine firing mechanism, Serial No. 406,236, filed August 9, 1941, respectively.

There is also provided within the plate 21 a second aperture or filler hole adapted to be closed

by a cover or plate 26 secured thereto as by the bolts 27 thereby to exclude water or moisture from an explosive charge 28 introduced within the casing through the filler hole.

There is also provided a faired member 29 comprising a semicircular flat plate 31 and a curved plate 32 secured thereto. The faired member 29 is tacked to the front portion of the mine substantially at the junction of the plates 21 and 23 in any suitable manner as by spot welding the parts together at intervals as at 33 and to the mine casing as at 34 substantially as shown whereby the mine presents a symmetrical front to the air when released from an aircraft in flight thereby to maintain the flight of the mine along a predetermined path of travel through the air. The plate 31 is provided with a pair of apertures 35 adapted to admit water to the interior of the faired member 29 and cause the faired member 29 to be ripped clear of the mine casing as the mine strikes the surface of the water thereby exposing the surface of the plate 23 to the action of the water. The plate 23 now presents to the water a control surface disposed at an angle with respect to the direction of movement of the mine whereby the pressure of the water against the control surface causes the mine to veer and pursue a different course within the water such that the axis of the mine is turned substantially normal to the path of travel and thus the velocity of the mine within the water is quickly checked sufficiently to reduce the vertical component of the travel of the mine within the water to the terminal velocity of the mine within the water or to a value less than the terminal velocity of the mine within the water. The terminal velocity, as employed herein, may be defined as the maximum rate of descent of the mine within the water when the downward movement of the mine within the water is effected solely by the gravitational pull on the mine during the time the mine is submerged.

When the downward movement of the mine has been substantially arrested as the result of a change in the angular position of the axis of the mine with respect to the path of travel thereof in response to the pressure of the water against the control surface of the plate 23, the mine sinks within the water at a greatly reduced rate of travel and comes to rest on the bed of the body of water without damage or injury to the casing or to the firing control mechanism therein, the force of impact of the mine against the bed being insufficient to cause the mine to be buried within the bed.

On Fig. 4 is shown an alternative form of the device applied to a mine 36 comprising a casing 37 generally similar to the casing of the mine of Fig. 1, but different from the casing of Fig. 1 in that the nose of the mine is rounded and provided with a cup-shaped reinforcing plate 38 secured thereto in any suitable manner thereby to strengthen the nose of the casing and increase the resistance thereof to damage or injury as the result of the mine striking the surface or bed of a body of water. The cup-shaped member 38 is provided with a cap or cover 39 thereby to support and protect one end of an induction pickup coil arranged within the mine. The mine is also provided with a flanged tubular member 41 secured to the nose of the casing in any suitable manner as by welding the parts together and having the axis thereof in alignment with the axis of the casing. Secured to the tubular member 41 in any suitable manner as by

threading the parts together is a deflecting device or plug 42 composed preferably of metal suitable for the purpose and having a recessed portion 43 therein adapted to receive a tool thereby to facilitate the assembly of the plug with the member 41. The plug is preferably cylindrical in shape and provided with a control surface 44 arranged at an angle with the respect to the axis of the plug substantially as shown.

There is also provided a complementary faired device 45 composed of material suitable for the purpose such as wood and secured to the plug 42 by the screws 46, the heads of the screws being preferably countersunk within the faired device 45 substantially as shown. The faired device is preferably of the same diameter as the plug 42 and when assembled thereon presents a symmetrical surface to the air whereby the mine follows a predetermined line of flight when released from the aircraft.

When the mine strikes the surface of the water, however, the force of the water against the faired device 45 causes the screws 46 to be sheared or otherwise broken and the faired device to be ripped clear of the plug 42. The inclined surface of the plug 42 is now exposed to the control action of the water and the mine is thus deflected or veered from the original path of travel thereof through the water by the pressure of the water against the deflecting surface of the device 42 until the downward movement of the mine within the water is decreased to a value equal to or less than the terminal velocity of the mine within the water; the mine thereafter sinking within the water at a greatly reduced velocity and striking the bed of the body of water with insufficient force to cause injury or damage to the casing of the mine or to the mine firing mechanism within the casing, the mine thus coming to rest on the bed of the body of water without entering the bed.

Briefly stated in summary, the present invention contemplates the provision of a faired member detachably secured to the nose of the mine whereby the mine is adapted to follow a predetermined line of flight when launched from an aircraft in flight and in which, when the mine strikes the surface of the water, a control surface is automatically made effective to engage the water and deflect the mine from the original path of travel thereof and thereby reduce the rate of downward movement of the mine within the water sufficiently to prevent damage or injury to the mine casing and to the mine firing control mechanism therein as the mine strikes the bed of the body of water. Furthermore, by deflecting the course of the mine in the manner disclosed during the downward movement of the mine within the water, the mine is prevented from striking the bed of the body of water with a force sufficient to cause the mine to be buried within the bed.

While the invention has been described with reference to two examples thereof which give satisfactory results, it will be understood by those skilled in the art to which the invention pertains, after understanding the invention, that various changes and modifications may be made without departing from the spirit and scope of the invention and it is our intention, therefore, in the appended claims to cover all such changes and modifications.

The invention herein described and claimed may be manufactured and used by or for the Government of the United States of America

for governmental purposes without payment of any royalties thereon or therefor.

What is claimed as new and desired to be secured by Letters Patent of the United States is:

1. In a ground mine of the character disclosed adapted to be planted on the bed of a body of water from an aircraft in flight, a cylindrical mine casing having a semicircular flat portion on the nose thereof arranged transverse to the axis of the mine, an inclined portion secured to said semicircular flat portion along the diameter thereof and to said casing, and a complementary semicircular faired device comprising a flat member in substantial alignment with said semicircular flat portion of the casing and detachably secured thereto and a curved member secured to said flat member and detachably secured to the cylindrical portion of the casing, said flat member having at least one aperture therein adapted to admit water to the interior of the faired device sufficient to cause the faired device to be detached from the casing by the pressure of the water therein as the mine strikes the surface of the water.

2. An aircraft planted marine ground mine, a casing for said mine, a faired device secured to the casing and having an exposed forward flat surface normal to the line of free flight of the mine through the air and adapted to be detached therefrom as the mine strikes the surface of the water; and means on said casing including an inclined surface to which the faired device is secured in matching relation and effective when said faired device has been detached for suddenly reducing the rate of the downward movement of the mine within the water.

3. An aircraft planted mine adapted to rest on the bed of a body of water, a deflecting surface on the nose of said mine adapted to cause the mine to tilt and veer within the water and thereby reduce the downward rate of travel therein; a faired member having an exposed flat forward surface normal to the line of free flight of the mine for rendering said deflecting surface ineffective to change the course of the mine during the flight thereof through the air; and frangible means for causing the faired member to be detached from the casing as the mine strikes the surface of the water.

4. A marine ground mine of the character disclosed adapted to be launched from an aircraft in flight, a cylindrical mine casing having a rounded nose thereon, a circular member secured to said nose in alignment with the axis of the casing and extending forwardly therefrom, a substantially flat control surface on said circular member arranged at an angle with respect to said axis and adapted to cause the mine to follow an erratic path of travel within the water thereby to reduce the rate of downward movement of the mine within the water, a complementary member adapted to render said control surface ineffective to change the line of flight of the mine during the free flight of the mine through the air, and means for detachably securing said complementary member to said circular member whereby the complementary member is detached therefrom by the force of impact of the complementary member against the surface of the water.

5. A marine ground mine of the character disclosed comprising, in combination, a cylindrical casing for said mine adapted to be launched from an aircraft in flight and come to rest on the bed of a body of water, a deflecting surface

7
on said casing adapted to cause the mine to deviate from the initial path of travel of the mine within the water until the axis of the mine is substantially normal to the instant path of travel thereof whereby the rate of downward movement of the mine is reduced to a value less than the terminal velocity of the mine within the water, and means frangibly secured to said deflecting surface and adapted to be removed therefrom as the mine strikes the surface of the water for rendering said control surface ineffective to change the line of flight of the mine during the free flight of the mine through the air, said means having an exposed flat forward surface perpendicular to the free line of flight.

6. A marine ground mine of the character disclosed adapted to be planted on a soft bed of a body of water from an aircraft in flight, a casing for said mine having a nose portion, a faired element frangibly connected to said nose portion and adapted to be detached therefrom as the mine strikes the surface of the water, and a deflecting member on said casing effective when the faired element has been detached for reducing the rate of travel of the mine through the water sufficiently to prevent the mine entering said bed, said faired element having an exposed flat forward surface perpendicular to the free line of flight of the mine through the air.

7. In a ground mine of the character disclosed adapted to be planted on the bed of a body of water from an aircraft in flight, a cylindrical mine casing having a nose portion, means on said nose portion forming an inclined surface transverse to the axis of the casing, a complementary faired device having an exposed forward flat surface perpendicular to said axis and arranged in matching engagement with said inclined surface whereby the forward exposed surface of the mine is rendered symmetrical when said faired device is secured thereto, and frangible means effective to secure said faired device to said inclined surface until detached therefrom upon impact of the faired device with the surface of the water.

8. A ground mine of the character disclosed adapted to be planted on the bed of a body of water from an aircraft in flight comprising, a casing for said mine, said casing having a nose portion, a deflecting surface on said nose portion

5 of the casing for immediately reducing the rate of the downward movement of the mine within the water, a faired device adapted to be secured to said deflecting surface in matching engagement therewith and having an exposed forward flat surface portion perpendicular to the line of free flight of the mine through the air and effective to render said forward portion of the mine symmetrical whereby said reflecting surface is ineffective to change said line of flight, and means for frangibly securing said faired device to said reflecting surface whereby the faired device is immediately detached therefrom as the mine strikes the water.

15 9. A marine ground mine of the character disclosed adapted to be launched from an aircraft in flight comprising, in combination, a cylindrical mine casing having a nose portion, a substantially flat control surface arranged on said nose portion at an angle with respect to the axis of the casing and adapted to cause the mine to follow an erratic path of travel within the water thereby to reduce the rate of downward movement of the mine within the water, a complementary member arranged on said nose portion 20 in matching engagement with said control surface and having an exposed forward flat surface normal to said axis, said complementary member being adapted to render said control surface ineffective to change the line of free flight of the mine through the air, and means for frangibly securing said complementary member to said control surface whereby the complementary member is detached therefrom by the force of impact of the complementary member against 25 the surface of the water.
